Attorney

UNITED STATES PATENT OFFICE.

CHARLES A. MEALY, OF PROVIDENCE, RHODE ISLAND, ASSIGNOR TO THE HADLEY COMPANY, OF PROVIDENCE, RHODE ISLAND.

WRIST-WATCH STRAP.

Application filed January 27, 1926. Serial No. 84,196.

This invention relates to certain new and useful improvements in wrist watch straps and relates more particularly to a strap which may be lengthened thereby to permit 5 of disengagement thereof from the wrist without disconnecting the strap ends from the watch.

The primary object of the invention is to provide improved and simplified means 10 for enabling the strap to be adjusted as to length so as to fit wrists of different sizes.

A further object of the invention is to provide means of the character mentioned which enables the adjustment to be easily 15 and quickly effected and to also provide means which can be economically produced.

In the drawings:—

Figure 1 is a side edge elevation of the invention, partly broken away and in section, the strap being shown in fragment,

Figure 2 is a top plan view the parts being in opened position, to lengthen the structure, and

Figure 3 is a section on line 3—3 of Figure 1.

In proceeding in accordance with the present invention a strap composed of sections 1 and 2 is employed, the outer ends of which sections are connected to the watch 30 and the inner ends of which are provided with loops 3 and 4.

The inner ends of the straps are spacedly connected by a connector composed of sections 5 and 6 hinged together at their ends 35 at 7'. Section 5 has sides 7, between which the sides 7" of section 6 are received.

Section 5 is formed with a series of struck-out parts in its bottom wall, which parts are bent or shaped to form hooks 8. The 40 hooks are spaced lengthwise of the section 5 and extend transversely thereof.

The loop 3 of the strap 1 is cut away as indicated at 9 to expose the central part of a pin or cross-bar 10, the pin being received 45 in the resultant spaced loop ends, and is headed at 11 so as to prevent axial movement thereof.

The strap section 2 is connected to the sides 7" of the connector section 6 by means 50 of a pin 12, which is received in the loop 4.

The pin ends project outwardly beyond the sides 7" of the section 6 and are received in keepers 10' provided therefor in the sides 7 of the section 5, thereby to hold the section 55 latched as shown in Fig. 1 of the drawings.

From the foregoing it will be seen that the strap may be easily and quickly adjusted to vary its length by merely engaging the pin 9 with the desired one of the hooks 8, without operating any extraneous parts or 60 the like. Further, the pin is confined between the two sections, as well as the several hooks, thus concealing these parts and preventing contact thereof with the wrist or person or other objects. 65

Having thus described my invention what I claim as new and desire to secure by Letters Patent is:—

1. In a wrist watch strap, a pair of strap sections, a pair of connector sections hinged together at their inner ends one of the connector sections having sides and having a series of spaced struck-out hooks between its sides and extending transversely across the bottom, a pin connected to an end of one 70 of the strap sections, said end of said strap section being cut away to expose the central part of the pin, said central part of the pin being engageable with a selected one of the hooks, and means to connect an end of the 75 other strap section to the outer end of the other connector section. 80

2. In a wrist watch strap, a pair of strap sections, a pair of connector sections hinged together at their inner ends, one of the connector sections having a series of hooks carried by the bottom thereof, a pin connected to an end of one of the strap sections, said end of said strap section having a cutaway 85 part to expose a part of the pin, said exposed part of the pin being engageable with a selected one of the hooks, and means to connect an end of the other strap section to the outer end of the other connector section. 90

3. In a wrist watch strap, a pair of strap sections, a pair of connector sections hinged together at their inner ends, a pin carried by one of the ends of one of the strap sections and having an exposed intermediate part, means to connect and end of the other 95 strap section to one of the connector sections, and a series of means carried by the other connector section to selectively engage the exposed intermediate part of the pin. 100

4. In a wrist watch strap, a pair of strap sections, a pair of connector sections carried by the respective strap sections and being hinged together at their inner ends, one of the strap sections having a loop formed 110

with a central cutaway part, a pin carried by the loop having said cutaway part, and a series of means carried by one of the connector sections to selectively engage the exposed part of the pin.

5. In a wrist watch strap, a pair of strap sections, a pair of connector sections hinged together at their inner ends, a pin carried by one of the strap sections, a series of 10 means carried by one of the connector sections and disposed between the sides thereof to selectively engage the pin, and means to connect an end of the other strap section to the other connector section.
- 15 6. In a wrist watch strap, a pair of strap sections, a pair of connector sections carried

by the respective strap sections and being hinged together at their inner ends, a series of hooks carried by one of the connector sections and located between the sides thereof, and means carried by one of the strap sections and selectively engageable with one of the hooks to connect said last named strap section to the first named connector section, the other connector section being movable to overlie the first connector section so as to hold the said means between the two connector sections. 20 25

In testimony whereof I have signed my name to this specification.

CHARLES A. MEALY.
